[57] **CLAIM**

The ornamental design for a bladder control receptacle, as shown and described.

DESCRIPTION

FIG. 1 is a perspective view of a bladder control receptacle showing my new design;

FIG. 2 is a front elevational view thereof;

FIG. 3 is a right side elevational view thereof, the left side elevational view being a mirror image thereof;

FIG. 4 is a top plan view thereof;

FIG. 5 is a bottom plan view thereof; and,

FIG. 6 is a rear elevational view thereof.

The broken line showing of an undergarment in FIG. 1 is for illustrative purpose only and forms no part of the design.
